UNITED STATES PATENT OFFICE.

CHESNEY L. JONES, OF PATERSON, NEW JERSEY.

HYDRAULIC VALVE.

Application filed March 7, 1924. Serial No. 697,577.

To all whom it may concern.

Be it known that I, CHESNEY L. JONES, a citizen of the United States, and residing at Paterson, in the county of Passaic and State 5 of New Jersey, have invented certain new and useful Improvements in Hydraulic Valves, of which the following is a specification, such as will enable those skilled in the art to which it appertains to make and 10 use the same.

This invention relates to hydraulic valves and particularly to devices of this class designed to control the operation of the ram or rams of presses or it may be used for 15 other purposes; and the object of the invention is to provide a valve device which is so constructed in units as to permit of the coupling of one or more valve units together; a further object being to provide a 20 valve device which will provide for increased press speed over other types of valves of this class now employed, and which will be absolute in its control and which will readily govern the operation of 25 the press without shock or strain to the equipment thereof; a further object being to provide ports or passages in the valve of greater area than the pipes or other communications coupled with said valve; a still 30 further object being to provide improved means for sealing the cylinder in the valve casing as well as for sealing the piston or pistons in said cylinder to avoid the leakage or by-pass of water around the pistons and 35 cylinder; and with these and other objects in view, the invention consists in a valve device of the class and for the purpose specified, which is simple in construction and operation, and efficient in use and which is 40 constructed and operated as hereinafter described and claimed.

The invention is fully disclosed in the following specification, of which the accompanying drawing forms a part, in which the 45 separate parts of my improvement are designated by suitable reference characters in each of the views, and in which:

Fig. 1 is a sectional view through a dual valve construction made in accordance with 50 my invention and showing predetermined mechanisms in full lines and in section and with parts of the construction broken away.

Fig. 2 is a partial section on the line 2—2 of Fig. 1; and,

Fig. 3 is a plan view of the construction 55

shown in Fig. 1 on a reduced scale and showing certain details of construction not shown in Fig. 1.

In the accompanying drawing, I have shown for the purpose of illustrating one 60 use of my invention, two substantially similar valve bodies 5 and 5^a bolted together as shown at 6. The valve body 5 is provided with an intake port 7 for the supply of water under predetermined pressure to the 65 valve and with a port 8 which leads to the press for actuating the ram thereof, blocks 9 being provided for coupling intake discharge pipes 10 and 11 respectively with the ports 7 and 8. The valve body 5 is also 70 provided with another port 12 which communicates with a similar port 13 in the valve body 5^a when the valve bodies are coupled together. The ports 12 and 13 form a by-pass passage for placing the 75 separate valve bodies in communication as hereinafter set out. The valve body 5^a is provided with a port 14 which also leads to or is coupled with the press through the discharge pipe 15 similar to the pipe 11, and a 80 threaded port 16 is also formed in the valve body 5^a which may, if desired, receive a plug in using two valve bodies as illustrated in Fig. 1 of the drawing. In coupling the 85 valve bodies together in the manner shown a suitable gasket 17 is placed between the valve bodies in juxtaposition to the bores 12 and 13.

The valve bodies 5 and 5^a are provided with bores 18 which extend longitudinally 90 therethrough and which open through the opposite ends thereof, the bores being reduced at one end as shown at 19. Waste pipes 20 are mounted in connection with caps 21 on said ends of the valve bodies and 95 communicate with the reduced portions 19 of said bores. The other end portion of the valve bodies 5 and 5^a are provided with annular recesses 22 having ports 23 which open outwardly through said valve bodies. The 100 bores 18 are also provided with annular chambers 23 and 24 with which the ports 7—12 and 8 respectively communicate in the valve body 5, while the ports 13—16 and 14 communicate respectively with said chambers of the valve body 5^a.

Mounted within the bores 18 of the separate valve bodies are tubular cylinders 25, one end portion of which abuts the piston stops 26 located in juxtaposition to the re- 110

duced portions 19 of the bores while the other end of said cylinders are retained in position by removable plates 27 which are preferably circular in form and provided 5 with peripheral grooves 28, one of which is shown in Fig. 1 of the drawing and the plates 27 are provided with central bores 29 having glands 30, and passed through and movable in the bores and stuffing boxes are 10 the shafts 31 of pistons 32. The pistons 32 in the construction shown are each composed of two piston heads 33 and 34 coupled together by a reduced shank portion 35, and one of the complete pistons is clearly shown 15 in Fig. 1 of the drawing.

The cylinders 25 are provided in the periphery thereof and at spaced intervals longitudinally of said cylinders with packing ring grooves 36, one groove being preferably 20 located at either side of the chambers 23 and 24 and placed in these grooves are endless rings composed of leather or similar material. At the base of the grooves 36 are smaller grooves 38 preferably located centrally of the grooves 36 and a plurality of apertures 39 spaced circumferentially of the cylinders 25 are so arranged or formed as to communicate with the grooves 38 and the chambers 23 and 24, thus placing said chambers 25 in communication with the grooves 38 in back of the rings 37 mounted in the ring grooves 36. The cylinders 25 are also provided at one end with a plurality of circumferentially spaced apertures 40 which are 30 adapted to register with the recesses 22. The cylinders 25 are provided with two sets 41 and 42 of elongated apertures spaced circumferentially of said cylinders and which register with the chambers 23 and 24 respectively, and while I have shown this specific formation of the apertures 41 and 42, it will be understood that any form of apertures or arrangement thereof for placing the 40 interior of the cylinders in communication with the chambers 23 and 24 may be provided.

The piston heads 33 and 34 are each provided with two ring grooves 43 similar in shape and construction to the ring grooves 36 and in which packing rings 44 are mounted, said rings being composed of leather or similar material, and the bores 45 which communicate with the grooves 43 in both of the piston heads 33 and 34 are directed toward the reduced shank 35 of the piston or into the chamber formed between said shank and the cylinder wall.

Split rings 46 are mounted in the grooves 28 of the plates 27 and carry a radially extending arm 47 with which is connected a link 48, and a lever 49 is pivotally mounted in connection with the free end of the piston shaft 31 as shown at 50 and is also pivoted to the link 48 as shown at 51 and by means 60 of this construction, the piston may be

moved longitudinally of the cylinder. Only one of the lever constructions are shown in Fig. 3 of the accompanying drawing, but it will be understood that both of the pistons will be provided with similar levers or two or more pistons may be actuated through one lever mechanism if desired.

As hereinbefore stated, it will be understood that one or more of the valve bodies may be employed in connection with a predetermined apparatus but in the drawing, as the positions of the pistons are shown in the separate valve bodies 5 and 5^a water will enter the valve body 5 from the portion 7 and from the chamber 23 therein will pass to the chamber 23 of the valve body 5^a from the ports 12 and 13 and from said last named chamber into the cylinder 25 through the ports 41 in said cylinder, thence out through the ports 42 in the last named cylinder and into the pipe 15 through the chamber 24 and port 14 and as the piston 32 in the last named cylinder is in its innermost position, the ram of a press will be actuated at full speed, but by moving the piston outwardly the speed may be decreased at the will of the operator and the flow of water throttled through the ports 41 and 42. To shut off the supply of water, the piston within the cylinder of the valve body 5 is moved into position to seal the apertures 42 in said cylinder. In directing the flow of water to the pipe 11 through the port 8, the piston 32 in the valve body 5 will be moved into its innermost position or in any desired position to control and regulate the desired press speed, in which a predetermined area of the ports 42 is uncovered. In this operation, it will be apparent that the piston 32 in the valve body 5^a will be moved into a position similar to the position of the piston 32 in the valve body 5 as shown in Fig. 1 of the drawing. It will also be understood that both pistons may be moved and retained in a position similar to the position of the piston shown in the body 5^a in Fig. 1 of the drawing in the operation of two or more presses.

In the above operation of the valve, it will be understood that the water under pressure enters the apertures 39 as well as the apertures 45 whereby said water is admitted into recesses back of the rings 37 and 44, which operation causes the expansion of said rings against the walls of the cylinder to provide a seal preventing the leakage of water between the periphery of the cylinder and the valve body in which it is mounted and also to effecting a perfect sealing of the piston heads in the cylinders in their operation.

It will be understood that the waste water in the pipes 11 and 15 or ports 8 and 14 will be discharged through the waste pipes 20 and in the event of the presence of water outwardly of the piston heads 34 in the 130

separate cylinders, this water will be discharged through the ports 40, recesses 22 and ports 23, which latter construction is designed to relieve any pressure in the cylinders in the event of a leakage by the piston heads should any of the packing rings thereof become worn out or be of faulty construction. It will be noted that the spaces between the grooves 43 in the piston heads 33 is greater than the length of the apertures 42 in the cylinder, whereby said apertures or ports in the cylinder may be entirely sealed when desired, by properly positioning the piston heads 33 thereover. It will also be noted that the area of all of the ports in the cylinder is greater than the area of the connecting pipes, and by reason of this construction I eliminate the friction losses which is common in the present type of valve constructions, thus providing for an increased press speed, and due to the simplicity of the device, position, action and ease of control is experienced in the use of said valves.

25 It is also preferred that the chambers 22 in the valve bodies 5 and 5^a be placed in communication with the waste pipes 20 this being accomplished by small tubings 52 in communication with said discharge ports and said pipes as shown in Fig. 1 of the drawing and these pipes are omitted in Figs. 2 and 3 of the drawing. The purpose of coupling the two water discharging means of the bodies 5 and 5^a is to equalize pressure in the opposite end portions of the cylinders, in the discharge of water through the waste pipes 20, thus producing a balancing effect on the pistons in the separate cylinders.

Having fully described my invention, 40 what I claim as new and desire to secure by Letters Patent, is:

1. A device of the class described comprising two substantially similar valve bodies, cylinders mounted in said bodies, pistons in said cylinders, one of said valve bodies being provided with an intake port and both of said valve bodies being provided with discharge ports, intercommunicating ports in the separate valve bodies, 45 and said cylinders being ported to register with the separate ports of the valve bodies.

2. A device of the class described comprising two substantially similar valve bodies, cylinders mounted in said bodies, pistons in said cylinders, one of said valve bodies being provided with an intake port and both of said valve bodies being provided with discharge ports, intercommunicating ports in the separate valve bodies, 50 said cylinders being ported to register with the separate ports of the valve bodies, and the areas of the cylinder ports being greater than the area of the ports in the valve bodies.

3. A device of the class described com-

prising two substantially similar valve bodies, cylinders mounted in said bodies, pistons in said cylinders, one of said valve bodies being provided with an intake port and both of said valve bodies being provided with discharge ports, intercommunicating ports in the separate valve bodies, 55 said cylinders being ported to register with the separate ports of the valve bodies, the areas of the cylinder ports being greater than the area of the ports in the valve bodies and the body ports and cylinder ports being placed in communication through chambers formed between said valve bodies and cylinders.

4. A device of the class described comprising two substantially similar valve bodies, cylinders mounted in said bodies, pistons in said cylinders, one of said valve bodies being provided with an intake port and both of said valve bodies being provided with discharge ports, intercommunicating ports in the separate valve bodies, 60 said cylinders being ported to register with the separate ports of the valve bodies, the areas of the cylinder ports being greater than the area of the ports in the valve bodies, the body ports and cylinder ports being placed in communication through chambers formed between said valve bodies and cylinders, and means disposed at the opposite sides of said chambers for preventing leakage between the valve bodies and cylinders around the said chambers.

5. A device of the class described comprising two substantially similar valve bodies, cylinders mounted in said bodies, pistons in said cylinders, one of said valve bodies being provided with an intake port and both of said valve bodies being provided with discharge ports, intercommunicating ports in the separate valve bodies, 65 said cylinders being ported to register with the separate ports of the valve bodies, the areas of the cylinder ports being greater than the area of the ports in the valve bodies, the body ports and cylinder ports being placed in communication through chambers formed between said valve bodies and cylinders, and means disposed at the opposite sides of said chambers for preventing leakage between the valve bodies and cylinders around the said chambers, said means comprising continuous packing rings and ports placing the back of said rings in communication 70 with said chambers.

6. A device of the class described comprising two substantially similar valve bodies, cylinders mounted in said bodies, pistons in said cylinders, one of said valve bodies being provided with an intake port and both of said valve bodies being provided with discharge ports, intercommunicating ports in the separate valve bodies, 75 said cylinders being ported to register with the separate ports of the valve bodies, the areas of the cylinder ports being greater than the area of the ports in the valve bodies, the body ports and cylinder ports being placed in communication through chambers formed between said valve bodies and cylinders, and means disposed at the opposite sides of said chambers for preventing leakage between the valve bodies and cylinders around the said chambers.

separate ports of the valve bodies, the areas of the cylinder ports being greater than the area of the ports in the valve bodies, the body ports and cylinder ports being placed in communication through chambers formed between said valve bodies and cylinders, means disposed at the opposite sides of said chambers for preventing leakage between the valve bodies and cylinders around the said chambers, said means comprising continuous packing rings and ports placing the back of said rings in communication with said chambers, and the movement of the pistons in the separate cylinders controlling said intake and discharge ports.

7. A device of the class described comprising two substantially similar valve bodies, cylinders mounted in said bodies, pistons in said cylinders, one of said valve bodies being provided with an intake port and both of said valve bodies being provided with discharge ports, intercommunicating ports in the separate valve bodies, said cylinders being ported to register with the separate ports of the valve bodies, the areas of the cylinder ports being greater than the area of the ports in the valve bodies, the body ports and cylinder ports being placed in communication through chambers formed between said valve bodies and cylinders, means disposed at the opposite sides of said chambers for preventing leakage between the valve bodies and cylinders around the said chambers, said means comprising continuous packing rings and ports placing the back of said rings in communication with said chambers, the movement of the pistons in the separate cylinders controlling said intake and discharge ports, and waste pipes in communication with one end of said cylinders.

8. A device of the class described comprising two substantially similar valve bodies, cylinders mounted in said bodies, pistons in said cylinders, one of said valve bodies being provided with an intake port and both of said valve bodies being provided with discharge ports, intercommunicating ports in the separate valve bodies, said cylinders being ported to register with the separate ports of the valve bodies, the areas of the cylinder ports being greater than the area of the ports in the valve bodies, the body ports and cylinder ports being placed in communication through chambers formed between said valve bodies and cylinders, means disposed at the opposite sides of said chambers for preventing leakage between the valve bodies and cylinders around the said chambers, said means comprising continuous packing rings and ports placing the back of said rings in communication with said chambers, the movement of the pistons in the separate cylinders controlling said intake and discharge ports, waste pipes

in communication with one end of said cylinders, and means for relieving the pressure in the other ends of the cylinders.

9. In a valve of the class described comprising a body, a cylinder mounted in said body, communicating ports in said body and cylinder, said ports being placed in communication through an enlarged chamber, and said cylinder being provided in the periphery thereof and at the opposite sides of said chamber with ring grooves having annular recesses at the base thereof, and ports for placing said recesses in communication with said chamber.

10. In a device of the class described provided with a cylinder and a member mounted to reciprocate therein, means for sealing said member comprising a continuous annular ring mounted in a groove in the periphery of said member, the base of said groove being recessed and said member being provided with apertures opening outwardly through said member and communicating with said recess whereby prevailing pressure around said member will operate to retain said ring in firm engagement with the cylinder wall.

11. In a device of the class described provided with a cylinder and a member mounted to reciprocate therein, means for sealing said member comprising a continuous annular ring mounted in a groove in the periphery of said member, the base of said groove being recessed and said member being provided with apertures opening outwardly through said member and communicating with said recess whereby prevailing pressure around said member will operate to retain said ring in firm engagement with the cylinder wall, and said ring being composed of fibrous material.

12. In a device of the class described comprising a body, a cylinder mounted in said body, said cylinder being provided on the periphery thereof with spaced and circumferential grooves, sealing units adapted to be mounted in the grooves of said cylinder to affect a seal between the cylinder and said body, said cylinder being provided inwardly of the sealing units with circumferential grooves of less transverse dimensions than said units, and means for exposing said last named grooves and the inner faces of said sealing units to the prevailing pressure in the cylinder to retain the outer faces of said sealing units in firm engagement with said body.

13. In a device of the class described comprising a body, a cylinder the periphery of which is provided in spaced relation longitudinally of the cylinder with annular ring grooves, fibrous sealing rings fashioned to fit snugly in said grooves, annular chambers formed in said cylinder within the inner faces of said rings and of less transverse di-

mensions than the corresponding dimensions of said rings, and means for exposing said chambers and the inner faces of said rings to the prevailing pressure in the cylinder 5 to retain the outer faces of said rings in connection with said body.

14. In a valve of the class described comprising a body, a cylinder mounted in said body, communicating ports in said body and cylinder, said ports being placed in communication through an enlarged chamber, a plurality of sealing rings mounted in grooves formed in the cylinder at the opposite sides of said chamber, and means in-

volving annular grooves located inwardly 15 of said sealing rings for exposing the pressure prevailing in said chamber to the inner faces of said sealing rings to expand the same into firm engagement with said body.

20 In testimony that I claim the foregoing as my invention, I have signed my name in presence of the subscribing witnesses this 29th day of February, 1924.

CHESNEY L. JONES.
